PAPER TOWEL DISPENSER PACKAGE

Clarence A. Rost, Missoula, Mont.

Application June 21, 1941, Serial No. 399,155

6 Claims. (Cl. 206—57)

The present invention relates to paper towel dispenser packages and to supports therefor.

The primary object of the invention is to provide a package of paper towels constructed so as to provide for the ready removal of a single 5 towel from the package.

Another object is to provide a pack of paper towels and a holder for supporting the same on a wall in which the pack has incorporated therein means for detachably engaging the holder so that 10 a new pack may be quickly engaged with the holder when a pack is used up.

A further object is to provide a pack of paper towels in which means are provided for facilitating the ready removal of single towels from the pack, said means comprising a tab carried by each sheet and connected by an easily severed portion to an overlying sheet whereby the tab on an underlying sheet will be raised to a 15 position to be readily grasped by the act of tearing the top sheet from the pack.

Other objects and advantages of the invention will be apparent from the detailed description of the invention with reference to the accompanying drawing which forms a part hereof and 20 in which

Fig. 1 is a plan view of a pack of towels embodying the invention, shown assembled with its holder and with parts broken away;

Fig. 2 is a section on the line 2—2 of Fig. 1,

Fig. 3 is a detail view of several sheets opened up showing the manner forming the pack and the tab construction;

Fig. 4 is a layout showing the cuts formed in the strip to separate the same into leaves with connecting tabs, and

Fig. 5 is a plan view of a pack of towels with a modified tab construction.

Referring now more particularly to the details of the invention, the pad or package of 40 towels 5 comprises a plurality of sheets 6 of suitable absorbent paper bound together along one edge. The size and number of leaves or sheets in the package may be varied as desired and may be made of suitable absorbent paper as usually employed for this purpose.

The pad is preferably formed from a continuous strip of suitable absorbent paper which is progressively folded back and forth zig-zag fashion a plurality of times to form the superposed leaves or sheets 6 constituting the individual towels.

The strip of paper from which the leaves are formed is provided with transversely extending cuts or slits at intervals, said slits defining the sides of the towel leaves and being arranged so as to form on each underlying leaf a tab connected to the next overlying leaf by an unsevered portion of the strip. In the embodiment of the invention shown in Figs. 1 to 4, the transverse slits

1 are disposed substantially coincident with the lines of fold and begin a short distance from the upper marginal edge of the strip, continue substantially along the line of the lines of fold and diverge diagonally laterally as a branch cut 8 and terminate short of the lower marginal edge as indicated at 9. These cuts produce on each underlying leaf an integral offset tab 10 joined to the next overlying leaf by an integral unsevered portion 11 of the strip. In the formed pad or package, the tabs 10 of successive leaves are disposed on alternate sides of the pack. When the top leaf is torn off the tab 10 on the underlying leaf, due to the connecting part 11, is raised and the leaf carrying it may also be raised slightly from the underlying leaves as the part 11 is torn through.

The strip is also provided with a broken row of slits or perforations 12 extending parallel with and spaced from the upper edge, the portion 13 of the pad above the weakened line provided by the slits 12 forming a back for binding. The unsevered portion joining the leaves at the ends of the portion 13 facilitates manufacture as it holds the strip in a continuous piece during the slitting, folding and binding.

The pad of towels formed by the slit and folded strip is provided with a binding comprising a face strip 14 and a backing strip 15 of substantially the same width and length as the portion 13. A narrow spacer strip 16 is centered on the strip 15 between the same and the bottom sheet of the portion 13 for the purpose of spacing the backing strip 15 from the pad. The strips 14, 15 and 16 35 may be formed of cardboard or fibre-board of sufficient thickness and rigidity to form a firm and fairly rigid binding for the pad and are fastened by suitable staples 17 passing through the strips and the portion 13 of the pad. An inner backing strip 15' is preferably provided between the spacer strip 16 and the bottom sheet of the pad.

The backing strip 15 comprises the means for mounting the pad in the holder 18. The holder 45 18, which may be made of metal, plastic or other suitable material, is in the form of a flattened slotted tube or channel member open at least on one end to receive the backing strip 15. The 50 channel shaped holder 18 includes a bottom or back 19, adapted to be fastened on a vertical wall or other support by means of screws 20, and in-turned flanges 21 which define a longitudinal slot 22 to accommodate the spacing strip 16 when the backing strip 15 is slid endwise into the 55 holder. When mounting the pad, the channel shaped holder member 18 is fastened on a wall or the like and the pad is engaged therewith by inserting one end of the strip 15 into the open end of the channel with the in-turned flanges 21 60 disposed between the strips 15 and 15'. The

spacer strip 16 will occupy the slot 22 between the edges of the flanges 21.

In the modified form of the invention shown in Fig. 5, the pad is formed in the same general manner as described above, except that the tabs 110 are formed substantially midway of the upper and lower edges of the leaves. This is accomplished by forming the edge slits 107 beginning short of the upper edge and with a branch 108 intermediate the edges which defines the upper edge of the tab 110. The lateral branch 108 terminates at an unsevered portion 110 at the tip of the tab and a return branch slit 108' extends from this unsevered portion back to the edge and continues at 107' to the lower edge of the strip.

From the above it will be apparent that the invention provides a convenient pad or package of paper towels having a novel binder which cooperates with a mounting member to support the pad for use and which permits ready replacement of used pads by a fresh pad. The use of the towels is greatly facilitated by the lifting tabs 10 which enable the user to grasp a single towel from the pad each time, thereby effecting an economy in use.

Although preferred embodiments of the invention have been shown and described by way of illustration, it will be understood that other modifications in the details of construction may be resorted to without departing from the spirit of the invention within the scope of the appended claims.

I claim:

1. A paper towel dispenser package comprising a continuous paper strip reversely folded at regular intervals to provide a stack of superposed leaves, said leaves being partially severed from each other along lines substantially following the lines of fold along the major portion thereof and departing therefrom to provide an integral tab extension on each underlying leaf, which tabs are cut from the next overlying leaf, and joined thereto by an integral unsevered connecting portion, a marginal binding portion along one edge of said pad extending normal to the lines of fold and partially severed from the body of the leaves, binding strips on the front and back of said marginal binding portion, and fastening means connecting said binding strips and said marginal binding portion.

2. A paper towel dispenser package comprising a continuous paper strip reversely folded at regular intervals to provide a stack of superposed leaves, said leaves being partially severed from each other along lines substantially following the lines of fold along the major portion thereof and departing therefrom to provide an integral tab extension on each underlying leaf, which tabs are cut from the next overlying leaf, and joined thereto by an integral unsevered connecting portion, a marginal binding portion along one edge of said pad extending normal to the lines of fold and partially severed from the body of the leaves, binding strips on the front and back of said marginal binding portion, a narrow spacer strip between the back binding strip and said binding portion and fastening means connecting said binding strips and spacing strip and said marginal binding portion.

3. A paper towel dispenser package comprising a continuous paper strip reversely folded at

regular intervals to provide a stack of superposed leaves, said leaves being partially severed from each other along lines substantially following the lines of fold along the major portion thereof and departing therefrom to provide an integral tab extension on each underlying leaf, which tabs are cut from the next overlying leaf, and joined thereto by an integral unsevered connecting portion, a marginal binding portion along one edge of said pad extending normal to the lines of fold and partially severed from the body of the leaves, binding strips on the front and back of said marginal binding portion, a narrow spacer strip between the back binding strip and said binding portion, fastening means connecting said binding strips and spacing strip and said marginal binding portion, and a slotted tubular holder open at one end to slidably receive the back binding strip to mount the pad on the holder.

20 4. A paper towel dispenser package comprising a pad of paper towels having a marginal binding portion along one edge thereof partially severed from the body of the leaves of the pad, binding strips on the front and back of said marginal binding portion, a narrow spacer strip between the back binding strip and said binding strips and said marginal binding portion and spacer strip, and a slotted tubular holder open at one end to slidably receive the back binding strip to mount the pad on the holder.

25 5. A paper towel dispenser package comprising a pad of superposed leaves, an inturned tab carried by each underlying leaf at one edge thereof and joined by a readily severable connection to a next superposed leaf, said pad having a marginal binding portion along one edge other than the edge at which said tabs are disposed and partially severed from the body of the leaves of the pad, binding strips on the front and back of said marginal binding portion, a narrow spacer strip between the back binding strip and said binding portion, fastening means connecting said binding strips and said marginal binding portion and spacer strip, and a slotted tubular holder open at one end to slidably receive the back binding strip to mount the pad on the holder.

30 6. A paper towel dispenser package comprising a continuous paper strip reversely folded at regular intervals to provide a stack of superposed leaves, said strip being cut transversely substantially on the lines of fold, said cuts beginning a short distance from one marginal edge and substantially following the line of fold along the major portion thereof and diverging therefrom adjacent the opposite marginal edge and terminating short of the last mentioned edge to define an integral tab extension on each leaf integrally joined by a weak connection to an adjacent leaf, said strip being provided with a line of interrupted cuts paralleling and spaced from said first mentioned marginal edge to provide a weakened tear line, the portion of said strip between said weakened tear line and the adjacent marginal edge forming in the stack a marginal binding portion, and binding means for said marginal binding portion, said binding means including a backing strip adapted to engage a slotted tubular holder for mounting the pad for use.
